Primary Examiner — Richard Edgar*Assistant Examiner* — Cheng Chen(74) *Attorney, Agent, or Firm* — Taft Stettinius & Hollister LLP; Stephen F. Rost(57) **CLAIM**

The ornamental design for an engine assembly, as shown and described.

DESCRIPTION

FIG. 1 is a top, right perspective view of a first embodiment of an engine assembly shown according to the present design;

FIG. 2 is a right side elevational view thereof;

FIG. 3 is a left side elevational view thereof;

FIG. 4 is a front end view thereof;

FIG. 5 is a rear end view thereof;

FIG. 6 is a top plan view thereof; and,

FIG. 7 is a bottom plan view thereof.

The broken lines illustrate environment and portions of the engine assembly that form no part of the claimed design.

1 Claim, 7 Drawing Sheets
